RESET MECHANISM FOR COUNTERS AND
THE LIKECharles S. Hazard, Andover, N. J., assignor to
Neptune Meter Company, a corporation of New
Jersey

Application November 29, 1938, Serial No. 242,877

18 Claims. (Cl. 235—144)

This invention relates to counters and more particularly to improvements in re-setting mechanism therefor.

Resetting mechanisms for counters such, for example, as may be used in computers for indicating the amount and cost of the substance counted, are often subjected to rough usage, that is, sudden jerking and very rapid operation of the reset shaft. Sudden jerking of the re-setting mechanism in certain types of counters sometimes causes the mechanism to miss or jump past the engageable lug associated with the indicating means, or should the mechanism engage the lug, a sudden jolt caused by the jerking or rapid movement of the reset shaft may cause the mechanism to vibrate and release the lug, thereby failing to properly reset the counter. Then again, where the indicating means are reset too rapidly they may, due to their own momentum, be thrown past the zero mark unless effective stop means are provided.

In accordance with the present invention these difficulties are overcome by the provision of a novel pick-up and stop arrangement wherein in the pick-up device is movable to a position upon initiation of a resetting operation where it will definitely contact and move the engageable lug of the counter mechanism toward zero position, the stop means being also movable to a position during the resetting operation to definitely engage and stop the engageable lug in zero position, the pick-up device and stop means cooperating to momentarily clamp the lug in zero position prior to their withdrawal from the path of movement of the engageable lug.

To free the counting mechanism of the re-setting mechanism at the completion of a re-setting operation, means are usually provided to effect a short pull-back movement on the re-setting mechanism. Pull-back devices provided for this purpose have heretofore included a spring which expends its energy during the pull-back movement, and since certain parts of the re-setting mechanism are adapted to be shifted near the end of the pull-back movement, an unusually strong spring is required to complete the shifting movement in order to properly free the counting mechanism for a new counting operation. The use of an unusually strong spring, however, not only adds considerably to the power required to turn the resetting shaft but also tends to introduce a destructive jolting action upon the mechanism during the pull-back movement.

In the present invention I have provided a

pull-back mechanism which is capable of effecting the complete disengagement of the counter and reset mechanisms by utilizing a spring of much less strength than heretofore used, thereby greatly minimizing the jolting action of pull-back mechanism heretofore experienced. My new pull-back mechanism includes a cam associated with the reset shaft having a cam surface extended outwardly from the shaft against which a follower is adapted to apply the force of a pull-back spring at a leverage which increases as the spring reacts. By varying the leverage at which the force of the pull-back spring is applied to the reset shaft, the resulting torque on the shaft is maintained substantially constant throughout the pull-back movement, the varying leverage largely compensating for the changing strength of the spring during rotation of the reset shaft.

One of the objects of this invention is to provide a resetting mechanism for counters having an arrangement of pick-up and zero stop elements whereby the indicating means may be reset to zero position without any possibility of being left behind or thrown past the zero mark.

Another object of this invention is to provide a resetting mechanism for counters or the like with means capable of effecting a pull back movement of sufficient power to effectively free the indicating means of the pick-up and zero stop elements when the indicating means reaches zero position with a minimum of jolting and jarring action.

Another object of this invention is to provide the resetting mechanism with means adapted to store energy during a resetting operation capable of effecting a pull-back torque on the reset shaft which is maintained substantially constant throughout a pull-back movement.

Another object of this invention is to provide a resetting mechanism for counters capable of effecting a resetting operation by a movement slightly greater than one complete revolution of the resetting mechanism.

A further object of this invention is to provide a structural arrangement incorporating the re-setting mechanism whereby a plurality of counters, such as provided in computing devices of the character adapted to indicate the amount and cost of a substance being counted, may be simultaneously reset to zero.

The above and other objects will become apparent upon considering the following description when taken in connection with the accompanying drawings, in which:

Figure 1 is a horizontal sectional view taken along the line 1—1 of Figure 2 showing a computer embodying the principles of the present invention;

5 Figure 2 is a vertical sectional view taken along line 2—2 of Figure 1 with parts broken away to show the interior mechanism of one of the numeral wheels;

10 Figure 3 is a vertical sectional view taken along line 3—3 of Figure 2;

Figure 4 is a vertical sectional view taken along line 4—4 of Figure 3 with parts broken away showing a portion of the resetting mechanism prior to the initiation of a resetting operation;

15 Figure 5 is a vertical sectional view similar to Figure 4 with the resetting mechanism shown in the extreme resetting position just prior to a pull-back movement, certain of the gears driven thereby being indicated in broken lines;

20 Figure 6 is a vertical sectional view taken along line 6—6 of Figure 1;

Figure 7 is a view in vertical elevation of the pull-back mechanism as viewed from the right-hand side of Figure 3;

25 Figure 8 is a vertical sectional view similar to Figure 2 showing certain elements of the resetting mechanism in different operative positions;

Figure 9 is a vertical sectional view taken along line 9—9 of Figure 1; and

30 Figure 10 is a view similar to Figure 9 with parts broken away and the elements in a different position.

A computer embodying the principles of the present invention is provided with a plurality of 35 counters adapted to indicate the amount and cost of substance or units being counted. The computer, as illustrated in Figures 1 and 2 of the drawings, comprises a pair of frame members 10 and 11 on which four identically constructed 40 counters A, B, C and D are mounted. The upper counters A and B may be provided with appropriate characters in the order of units, tens and hundreds representative of the cost of the substance being counted, while the lower counters C 45 and D may be provided with appropriate characters in the same order representative of the amount such as volume, length, number, etc., depending on the character of the substance being counted. Diametrically disposed between the 50 four counters is a form of my improved resetting mechanism which is adapted to reset all four counters simultaneously.

The resetting mechanism of my invention may 55 be used with counters where the numeral wheels are adapted to be reset either in a forward or reverse direction. For purposes of illustration, however, the resetting mechanism is shown with counters of the type disclosed in the copending application of Peter J. McLaren, Serial No. 60 206,570, filed May 7, 1938, now United States Patent No. 2,177,437, dated October 24, 1939, wherein the numeral wheels are adapted to be reset in a direction reverse to that of a counting operation.

65 Since all four of the counters are identical, the counter A only will be described in sufficient detail to give an understanding of the counter construction. Referring to Figures 1, 2, 9 and 10, counter A comprises a units wheel 12, a tens 70 wheel 13 and a hundreds wheel 14, all revolvably mounted upon a shaft 16 supported by bearings 17 and 18 in the frame members 10 and 11. The units wheel 12 is carried by a sleeve 20 revolvably mounted upon shaft 16. The sleeve 20 also carries a gear 22 by which the numeral wheel 12 is

driven during both the counting and resetting operations.

The tens wheel 13 is driven from the numeral wheel 12 by the usual Geneva type of transfer gearing 24. Secured to the sleeve 20 is a lock 5 disc 26 having provided in its periphery a single notch 27 (Fig. 2), the notch being bounded on one side of the disc by two teeth of a gear segment 28. A transfer pinion 30 is rotatably mounted on a plate 32 which is secured for rotation with shaft 16. Alternate teeth on the pinion 30 are cut short so that the lock disc is adapted to engage only the long teeth extending the full width of the pinion. The short teeth 36 which are adapted to be engaged by the teeth of 15 the gear segment 28 mesh with a gear 38 connected to a disc 40 and a notched detent wheel 42. The disc 40 is rotatably mounted on a sleeve 44, a ring 46 being provided to retain the disc in operative position. The tens wheel 13 is secured 20 to the sleeve 44 adjacent the disc 40. Pivotedly mounted upon a pin 48 carried on a side portion of the wheel 13 is a latch 50 provided with a finger 51 and a tail portion 52 (Figs. 9 and 10). The latch 50 is held on the pin 48 by the disc 40. 25 A spring 53 is connected to the latch 50 and to the side of the wheel 13 to normally maintain the finger 51 engaged between two adjacent teeth of the notched detent wheel 42. When the counter is driven forward by gear 22 the units wheel 12 30 and the disc 26 are revolved, enabling the notch 27 and teeth 28 to engage the teeth on the transfer pinion 30 to move the tens wheel 13 through one-tenth of a revolution for each complete revolution of the units wheel 12.

35 The transfer gearing 54 between the tens wheel 13 and the hundreds wheel 14 is identical with that of the transfer gearing 24. A lock disc 55 carried by the sleeve 44 drives the gear 56 and the notched detent wheel 58 through the medium 40 of the transfer pinion 60, the latch 62 providing a releasable connection between the wheel 14 and the notched detent wheel 58.

The transfer pinions 30 and 60 being carried by the shaft 16 for rotation in planetary paths 45 during rotation of the shaft render it possible to return the tens and hundreds wheels to zero position upon a single rotation of the shaft 16. Referring specifically to the transfer gearing 24, rotation of the shaft 16 moves the pinion 30 50 through an orbit about the shaft 16, the pinion being held against rotation on its own axis by the lock disc 26 save only for the partial rotation imparted to it when the notch 27 is encountered. While the pinion 30 is thus held against 55 rotation about its own axis during a movement in its planetary orbit, it locks with and drives the gear 38, which in turn causes the tens wheel 13 to be returned toward zero position. One complete planetary movement of the pinion 30 60 makes it possible for the wheel 13 to be returned toward zero through at least nine-tenths of a revolution. Since the wheel 13 can never stand further away from zero than nine-tenths of a revolution, it will therefore always be moved 65 through a distance sufficient to return it to zero position.

When the tens wheel 13 reaches zero position, the rotation of the shaft 16 may not be complete. Therefore, in order to release the wheel 70 13 from the pinion 30, a rockable member 63 having depending stops 64 is pivotally mounted for limited movement in openings 65 and 66 formed in the frame members 10 and 11. As the tens wheel 13 reaches zero position, the tail por- 75

tion 52 engages one of the stops 64 causing the latch 50 to move counterclockwise as viewed in Figure 9 to disengage the detent wheel 42. The tens wheel is thereupon retained in, or slightly beyond, zero position while the shaft 16 and the transfer pinion 30 are moved through the remaining portion of the resetting movement. The stop member 63 is biased to stopping position by action of gravity, the member being movable clockwise (see Figs. 2, 9 and 10) to permit the tens wheel to pass thereunder during a counting operation. Should the tens wheel be in zero position at the initiation of a resetting operation, the tail portion 52 will immediately engage the stop 64 and thereby retain the wheel at zero position throughout the resetting operation. The driving relation between the detent wheel 42 and the tens wheel 13 is re-established at the end of a resetting operation by the tension of the spring 53 which continually urges the latch 50 clockwise for locking engagement between adjacent teeth of the detent wheel 42.

The hundreds wheel 14 which is carried by a sleeve 67 is returned to zero position by the planetary movement of the pinion 68 in the same manner as just described in connection with the tens wheel 13, movement of the shaft 16 being controlled by the resetting mechanism through a gear 68. The units wheel 12 is reset to zero position independent of the tens and hundreds wheels by a pick-up mechanism to be hereinafter described.

Having described the type of counter with which my invention is illustrated, I shall now describe that form of the driving and resetting mechanism which embodies the novel features of my invention.

Each of the counters A, B, C and D are provided with an auxiliary shaft 11, 12, 13 and 14 respectively, appropriately mounted in bearings contained in the frame members 10 and 11. Diametrically located between the auxiliary shafts is a main resetting shaft 75 which is also mounted in frame members 10 and 11, the opposite ends of the shaft being extended beyond the frame members and provided with slotted sleeves 76 and 77 for the reception of a resetting handle (not shown). Keyed to shaft 12 for the purpose of driving the counters A and B during a counting operation is a friction clutch 80 comprising a sleeve 81 upon which a driving gear 82 is rotatably mounted for frictional engagement with a spring element 83 adjustably held against the gear 82 by a ring nut 84. Fixed to the sleeve 81 is a gear 85 which meshes with a gear 86 carried by a sleeve 87 rotatably mounted upon shaft 11. The gear 86 in turn meshes with the gear 22 operatively connected to the units wheel 12, of counter A. Counter B is driven from shaft 72 by a gear 88 which meshes with a gear 22b carried by a sleeve 20b upon which units wheel 12b is secured. The driving gear 82 may be driven directly from a measuring device or an interposed price variator mechanism (not shown), the friction clutch 80 permitting the counters to be reset independently thereof.

Counters C and D are driven by an arrangement similar to that described in connection with the units wheels of counters A and B, that is, a driving gear 90 meshes with a friction clutch 91 carried by the shaft 13, (Fig. 2) which in turn meshes with a gear 92 operatively connected with the units wheel of counter C. The friction clutch 91 also drives the shaft 14 by meshing with gear 93, the units wheel of counter D being driven

from shaft 14 by gears 94 and 95 (Fig. 3) similarly as in the case of the units wheel of counter B.

The mechanism for controlling the movement of the main resetting shaft and therefore the entire resetting mechanism is best illustrated in Figs. 1, 3, 4, 5 and 6. Surrounding the sleeve 77 and secured to the frame member 11 is a stationary lock disc 100 having a notch 101 to receive the head 102 of a latch 103 for the purpose of releasably locking the shaft 75 during a counting operation. Keyed to the shaft 75 is an arm 104 provided with an inclined slot 105, and adjacent the arm 104 is a gear 106 carried by a sleeve 107 rotatably mounted on the shaft 75. The latch 103 is pivotally mounted on an arm 108 secured to the side of the gear 106, the latch being provided with a pin 110 receivable in the inclined slot 105.

The initial resetting movement of shaft 75 causes the arm 104 to move clockwise camming the pin 110 upwardly in slot 105, thereby lifting the head of the latch 103 from engagement with the notch 101. When the pin reaches the left-hand end of the slot, continued rotation of the shaft 75 moves the crank arm 104, latch 103 and the arm 108 to revolve the gear 106 clockwise whereby the tens and hundreds wheels of the several counters may be simultaneously reset to zero position. The gear 106 engages a gear 112 rotatably mounted on the shaft 71, the gear 112 being secured by locking shims 114 to a gear 116 which in turn meshes with a gear 68 carried by the shaft 16. Thus, during the rotation of gear 106 the shaft 16 is driven to effect the resetting operation of the tens and hundreds wheels 13 and 14. The resetting of the tens and hundreds wheels of counter B is effected by the meshing engagement of gear 116 with gear 118 rotatably mounted on shaft 72, the latter in turn meshing with gear 120 secured to shaft 16b. The tens and hundreds wheels of counters C and D are reset from gear 106 by a gearing arrangement similar to that just described, the take-off gear 122 which meshes with gear 106 being indicated in Figure 5.

To prevent the gear 106 from being revolvable in a counterclockwise direction, a ratchet wheel 123 carried by the sleeve 107 is provided for engagement with a pawl 124 pivotally mounted on a stud 126 (see Fig. 6). The teeth of the ratchet wheel are so arranged that the pawl is adapted to engage a tooth on the ratchet wheel at the extreme resetting movement of the resetting mechanism. The pawl 124 and ratchet wheel 123 thus prevent the gear 106 from having any appreciable reverse movement during the pull-back movement.

In order to insure the stopping of the shaft 75 at the end of a resetting movement, a lever 130 is secured to the sleeve 77, the lever being provided with an inturned end 131 extended through an opening 132 in the frame member 11 to a position overlying the path of movement of the latch 103. The latch 103 is provided with an ear 134 adapted to engage the end 131 of lever 130 just prior to the completion of a resetting movement. The lever 130 is biased to the left as viewed in Figs. 1 and 4 by a compression spring 136. Extending through the opening 132 of frame member 11 is an abutment 137 adapted to engage and stop the lever 130 at the end of a resetting movement as indicated in Figure 5. When the shaft 75 is released, a pull-back mechanism to be hereinafter described effects a re-

verse movement upon the shaft whereby the pin 110 of the latch 103 is permitted to move along the slot 105 until the head 102 is lockingly received in the notch 101. Upon movement of the latch 103 into notch 101, the lever 130 is released from the ear 134 for return movement by spring 136 counterclockwise to the position indicated in Figure 4. The resetting mechanism is then ready to perform another resetting movement.

10 For the purpose of resetting the units wheels of the several counters, a novel pick-up and stop arrangement together with means for effecting a pull-back movement are shown in detail in Figures 1, 2, 3, 7 and 8. A pull-back cam 140 integral with sleeve 142 is mounted for rotation with the reset shaft 75. A gear 144 carried by the cam sleeve 142 meshes with a gear 145 rotatably mounted on shaft 71 (Fig. 2) and another gear 146 rotatably mounted on shaft 73. Secured to the gear 145 is a three-pronged member 150 to which a single-toothed pawl 151 is pivotally mounted at 152 on prong 153. Connected to the free end 154 of the pawl 151 and the prong 156 of member 150 is a spring 158 adapted to bias the pawl 151 for movement toward the shaft 71, the third prong 159 of member 150 being adapted to engage and retain the pawl in a predetermined position for rotation in a path about the shaft 71.

15 A ring 160 carried by the sleeve 87 for movement with gear 86 has a laterally extended lug 162 adapted to move in a path about the shaft 71 common to the path of movement of the pawl 151 whereby the pawl may engage and move the lug for a resetting movement toward zero position. After the lug 162 reaches zero position, the pawl 151 is withdrawn from the path of movement of the lug 162 by a pull-back movement which causes a tail portion 164 of the pawl 151 to engage a latch 165 which is pivotally mounted on a stud 166 carried by the frame member 10. The latch 165 is provided with two laterally extended arms 167 and 168. The arm 167 is extended through an opening 170 in the frame member 10 whereby movement of the latch 165 is limited by the opposed sides of the opening. A spring 172 engages the arm 167 to bias the latch 165 to the extreme right hand position indicated in Figure 2 for the purpose of positioning the other arm 168 for releasable engagement with the tail portion 164, whereby the pawl 151 may be withdrawn from engagement with prong 159 and moved to a non-pick-up position by clockwise movement of the gear 145 and returned to the pick-up position adjacent the prong 159 by counterclockwise movement of the gear 145.

20

25

30

35

40

45

50

55

Upon initiation of a resetting movement, the gear 145 as viewed in Figure 2 is moved counterclockwise whereby the tail portion 164 of the pawl 151 is disengaged from the latch 165, permitting the spring 158 to move the pawl 151 to the predetermined pick-up position in the path of the lug 162. The continued rotation of the reset shaft 75 causes the pawl 151 to revolve about shaft 71 for engagement with the extended lug 162 to drive the gear 86 counterclockwise and thus return the units wheel 12 toward zero position. The units wheel 12b of counter B is moved toward zero position simultaneously with the units wheel 12 by gear 86 through the connection including gear 85, shaft 72, and gears 88 and 22b. The unit wheels of counters C and D are returned toward zero position by a pick-up arrangement including a three-pronged member 150c, a pawl 151c and a latch 165c associated

with the gear 146 which is identical in construction to the pick-up arrangement described in connection with gear 145. The units wheels of the several counters are thus positively moved toward zero position by the resetting movement 5 of the reset shaft 75.

To provide a positive stop for the unit wheels of both sets of counters A, B and C, D a double armed pawl 175 in the form of a bell crank is rotatably mounted on the reset shaft 15. The 10 arm 176 of the pawl 175 is provided with a shoulder 177 to engage a lug 178 adjustably secured by bolts 180 and 181 on the gear 85 carried by shaft 72. The other arm 182 of the pawl 175 is provided with a shoulder 183 for engagement with a lug 184 adjustably secured to a gear 93 carried by the shaft 74. Pivotaly mounted on the pawl 175 is a small pawl 186 adapted to engage a projection 187 carried by the sleeve 142. The small pawl 186 is biased toward the shaft 20 75 by a spring 188, the pawl being provided with a tail portion 189 engageable with an abutment 190 on the pawl 175 to limit the movement of the small pawl 186 to a position for engagement with the projection 187.

Upon initiation of a resetting operation the projection 187 is moved clockwise as viewed in Figure 8, permitting the pawl 175 which is biased by a spring 192 to move clockwise for engagement with a pin 193 to position the shoulders 177 and 183 for stopping engagement with the lugs 178 and 184, respectively. To prevent the pawl 175 from prematurely engaging the lugs 178 and 184, a member 194 having a laterally projected lug 195 and biased clockwise by a spring 196 is rotatably mounted on shaft 12 for engagement with a shoulder 198 on the pawl 175. The lug 195 retains the pawl 175 momentarily until the shaft 15 has been moved through a partial rotation, whereupon the projection 187 engages an extended portion 199 of the member 194, causing the member to move and disengage the shoulder 198, the pawl 175 thereby being permitted to move on to zero stopping position. When the units wheels of the several counters reach zero position, the lugs 178 and 184 engage the shoulders 177 and 183 of the pawl 175, thereby definitely stopping the units wheels in zero position. 30 35 40 45

In order to effect a pull-back movement on the reset shaft 75 which exerts sufficient torque throughout the movement to effectively free the counters of the pick-up and stop elements, a pull-back mechanism has been provided comprising the cam 140 and a spring biased follower 200. The cam 140 has a portion 201 of the cam surface thereof extended outwardly from the axis of shaft 75 over which a roller 202 is adapted to move. The roller 202 is rotatably mounted on a pin 203 carried by a lever 204 which is pivotally mounted on a stud 206 located adjacent the shaft 75. An arcuate slot 207 is provided in the frame member 10 through which the roller 202 extends for engagement with the cam surface, the cam 140 and the lever 204 being located on opposite sides of the frame member 10. The lever 204 is provided with an elongated opening 208 through which one end of a rod 210 extends, the other end of the rod being pivoted to the frame member 10 at 212. A compression spring 214 is carried by the rod 210 so as to exert a force upon the lever 204. The axis about which the lever 204 is pivoted, being offset from the axis of the shaft 75, enables the roller 202 to move in an arc of a circle extending outwardly from the shaft 75. This relationship, which is

illustrated in Figure 7, is important since it provides a leverage which varies inversely as the stored energy of the spring 214 is varied. The spring 214 is compressed to its maximum extent when the roller 202 is in the position closest to the shaft 75, the roller being moved over the cam surface 201 in a direction away from the axis of the shaft 75 during the pull-back movement. The increasing distance between the shaft 75 and the roller 202 operates to increase the leverage at which the force of the spring is applied to the shaft as the spring reacts, whereby the pull-back torque on the shaft is maintained substantially constant throughout the pull-back movement.

The operation of the mechanism illustrated will be apparent from the foregoing description thereof but may be summarized as follows:

Upon initial movement of the reset shaft 75 the arm 104 (see Figs. 4 and 5) is moved clockwise, causing the pin 110 of the latch 103 to slide upwardly in the slot 105 thereby lifting the latch 103 from engagement with the locking disc 100. Continued rotation of the shaft 75 causes the pin 110 to become engaged in the left-hand end of the slot 105 whereby the latch 103 is forced to move in a clockwise direction about the shaft 75 to drive the gear 106. Meshing with the gear 106 are gears 112 and 122 which operate through a chain of gears to drive the shafts upon which the tens and hundreds wheels of the counters A, B, C and D are rotatably mounted. As described in connection with the counter mechanism the tens and hundreds wheels are reset to zero by the planetary movement of the transfer pinions thereof about the shafts supporting the numeral wheels.

The units wheels of the several counters are reset to zero by the resetting movement of shaft 75 which drives through gears 145 and 146 the pick-up devices containing the biased pawls 151 and 151c. The initial rotation of shaft 75 causes counterclockwise rotation of the pick-up devices about their respective shafts 71 and 73 whereby the pick-up pawls 151, 151c are released by the disengagement of the tail portions 164, 164c from latches 165 and 165c for movement to positions where the pick-up pawls, in their continued counter-clockwise movement about the shafts 71 and 73, are adapted to contact and move the engageable lugs 162, 162c associated with the upper and lower sets of counters toward zero position. The double-armed pawl 175 is released for movement to zero stopping position upon the initial movement of shaft 75, clockwise movement of the lug 187 permitting the pawl 175 to also move clockwise by action of the spring 192. Since the shaft 75 is moved through a movement greater than a single rotation, it is important to prevent the stops from moving into zero position immediately upon the initiation of a resetting operation. The latch 194 is therefore provided to momentarily intercept the double-armed pawl 175 at 195 when the pawl 175 is released by the lug 187, the latch 194 being later tripped by the lug 187 engaging the portion 199 to thereby permit the pawl 175 to move into zero stopping position where shoulders 177 and 183 are adapted to engage the lugs 178 and 184 respectively and thereby stop the units wheels at zero position. It will thus be apparent that the units wheels of the several counters will be returned and momentarily clamped in zero position by cooperation of the pick-up pawls 151 and 151c and the shoulders 177 and 183.

The pawls of the pick-up devices and the shoulders of the stop pawl are withdrawn from engagement with the counter mechanism by a pull-back movement on the shaft 75, the pull-back movement being counterclockwise as viewed in Figs. 2 and 7. Since the pick-up pawls are adapted to be shifted from their pick-up position during a pull-back movement and the zero stop pawl moved to a position free of the lugs 178 and 184 near the end of the pull-back movement, it is important that the pull-back torque be sufficiently strong throughout the pull-back movement to effectively free the counters of these pick-up and zero stop elements. The pull-back torque is maintained substantially constant throughout the pull-back movement by the structural arrangement of the pull-back cam 140 whereby the spring biased follower 200 is adapted to exert the force of the spring at a variable leverage, the leverage being increased as the spring reacts. The position of the roller 202 as shown in broken lines in Fig. 7 is that position assumed by the roller after the pull-back movement which follows each resetting operation, the roller 202 remaining in this position during counting operations.

Upon an initial resetting or clockwise movement of the shaft 75, the roller 202 is moved upwardly and to the right toward the shaft 75, as indicated in dot and dash lines in Fig. 7, by action of the cam surface 201. Since the shaft 75 is adapted to make a clockwise movement in excess of 360° for each resetting operation, the continued clockwise movement of the cam device 41 causes the roller to pass onto the surface 201a, which gradually permits the roller to return to the broken line position of Fig. 7, whereupon the roller 202 is again caused to move across the cam surface 201 to substantially the position indicated by the dot and dash lines. 40 This position of the roller 202 represents the end of the resetting movement just prior to the pull-back movement. When the reset shaft 75 is released, the roller is forced outwardly across the cam surface 201, causing the cam device 41 45 to rotate counterclockwise, and thereby accomplish the pull-back movement.

The movement of the roller 202, as indicated in Fig. 7, follows an arc of a circle from a point closely adjacent the shaft 75 to a point some 50 distance from the shaft 75, thus increasing the distance between the shaft and the point of contact on surface 201 as the spring expends its stored energy during the pull-back movement. The pick-up and stop elements and also the 55 arm 104 are thus shifted to their initial positions, the pin 110 being moved to the lower end of the slot 105 in the arm 104 whereby the latch 103 is lockingly received by the lock disc 100. The several counters are thus returned to zero 60 position and freed for a new counting operation.

While the construction illustrated and described is designed for resetting numeral wheels which are returned or moved backward to reset the same, the invention is also applicable to constructions 65 wherein the resetting direction of rotation of the numeral wheels or indicating means is forward as in a counting operation. It will also be evident that the invention is applicable to other types of mechanisms than the computer shown, 70 since the resetting of numeral wheels or the like takes place in the operation of many different devices. Moreover, it may be desirable to mount the pick-up and zero stop elements, the pull-back cam and the releasable locking means of 75

the resetting mechanism on the same shaft which supports the numeral wheels. Many modifications of my invention thus being possible, it is to be understood that the form of the invention herein shown and described is intended to be illustrative of a typical embodiment of the invention and is not intended to limit the scope thereof.

I claim:

- 10 1. In a counter provided with revolvable means movable away from zero position to perform a counting operation, the combination of resetting mechanism comprising pick-up means movable to a position upon initiation of a resetting operation 15 to return said revolvable means backwards toward zero position, stop means movable to a position during a resetting operation to engage and stop said revolvable means in zero position, and means operable after said revolvable means 20 reaches zero position to withdraw said pick-up means and said stop means from their operable position to free said revolvable means for a new counting operation.
2. In a counter provided with revolvable means 25 movable away from zero position to perform a counting operation, the combination of resetting mechanism comprising means including a pick-up element movable to a position upon initiation of a resetting operation to engage and move said revolvable means backwards toward zero position, means including a stop element movable to a position during a resetting operation to engage and stop said revolvable means in zero position, and means for storing energy during a resetting 30 operation to effect disengagement of said pick-up and stop elements from said revolvable means when said revolvable means has reached zero position.
3. In a counter provided with revolvable means 35 movable away from zero position to perform a counting operation, the combination of resetting mechanism comprising a shaft, means for actuating said shaft to effect a resetting operation, means including a pick-up element movable to a position upon initiation of a resetting operation to engage and move said revolvable means backwards toward zero position, means including a stop element movable to a position during a resetting operation to engage and stop said revolvable means in zero position, and means operatively connected to said shaft for storing energy 40 during a resetting operation to effect a pull-back movement on said shaft when said revolvable means has reached zero position, whereby said pick-up means and said stop means are moved to free said revolvable means for a new counting operation.
4. In a counter provided with revolvable means 45 movable away from zero position to perform a counting operation, said revolvable means including a member movable in an orbit during counting and resetting operations, the combination of resetting mechanism comprising a pick-up device including an element biased for movement into said orbit whereby said element is adapted to engage said member and return said revolvable means to zero position, a latch operable to retain said element free of said orbit during a counting 50 operation and to release said element for movement in said orbit during a resetting operation, and means for effecting a pull-back movement on said device after said revolvable means has reached zero position, said latch being positioned to engage and cause said element to move out of said orbit during said pull-back movement.
5. In a counter provided with revolvable means movable away from zero position to perform a counting operation, the combination of resetting mechanism comprising a shaft, means associated with said shaft to move said revolvable means backwards toward zero position during a resetting operation, stop means movable to a position to engage and stop said revolvable means in zero position, means for effecting a pull-back movement on said shaft after said revolvable means 55 has reached zero position, and means associated with said shaft to effect movement of said stop means to zero stopping position during a resetting operation and from said zero stopping position during said pull-back movement. 15
6. In a counter provided with revolvable means movable away from zero position to perform a counting operation, the combination of resetting mechanism comprising a shaft, means associated with said shaft to return said revolvable means 20 backwards toward zero position during a resetting operation, a pawl biased for movement to a position to engage and stop said revolvable means in zero position, means for effecting a pull-back movement on said shaft after said revolvable means 25 has reached zero position, and means including an element on said shaft and a latch on said pawl adapted to release said pawl during a resetting operation and to move said pawl from zero stopping position during the pull-back movement. 30
7. The combination defined in claim 6 provided further with an additional latch to intercept and temporarily hold the biased pawl in a non-stopping position when released, the element on said 35 shaft being arranged to trip said additional latch before said revolvable means reaches zero position.
8. In a counter provided with revolvable means movable away from zero position to perform a counting operation, the combination of resetting 40 mechanism comprising a shaft, means associated with said shaft adapted to engage and move said revolvable means backwards to zero upon a resetting movement of said shaft through one and a fraction revolutions, means including a pawl biased for movement to a position to engage and stop said revolvable means in zero position, means for effecting a pull-back movement on said shaft of an amount equal to said fraction of a revolution at the completion of said resetting 45 movement, and means associated with said shaft adapted to release said pawl during a resetting movement and to move said pawl from zero stopping position during the pull-back movement. 50
9. In a counter provided with revolvable means 55 movable away from zero position to perform a counting operation, the combination of resetting mechanism comprising a shaft, means associated with said shaft including an element biased to a position to engage and move said revolvable means backwards toward zero position during a resetting movement of said shaft through one and a fraction revolutions, means including a pawl biased for movement to a position to engage and stop said revolvable means in zero position, means for effecting a pull-back movement on said shaft of an amount equal to said fraction of a revolution at the completion of said resetting movement, means responsive to the pull-back movement of said shaft to effect the withdrawal of 60 said element and said pawl from engagement with said revolvable means, and means associated with said shaft to prevent said pawl from moving to zero stopping position until the shaft has moved through a partial rotation at least equal to said fraction of a revolution. 65
- 70
- 75

10. In a counter provided with revolvable means movable away from zero position to perform a counting operation, said revolvable means including a member movable in an orbit during 5 counting and resetting operations, the combination of resetting mechanism comprising a pick-up device including an element biased for movement into said orbit whereby said element is adapted to engage said member and return said 10 revolvable means to zero position, a latch operable to retain said element free of said orbit during a counting operation and to release said element for movement in said orbit during a resetting operation, said latch being positioned to 15 engage and cause said element to move out of said orbit during a pull-back movement, and means including a spring and leverage system for effecting said pull-back movement wherein the leverage at which said spring operates is increased as the spring reacts.

11. In a counter provided with revolvable means movable away from zero position to perform a counting operation, the combination of resetting mechanism comprising a shaft, means associated 25 with said shaft to move said revolvable means backwards toward zero position during a resetting operation, stop means biased for movement into the path of movement of said revolvable means to engage and stop said revolvable means 30 in zero position, means associated with said shaft adapted to withdraw said stop means from said path near the end of a pull-back movement on said shaft, and means including a spring and leverage system for effecting said pull-back movement wherein the leverage at which the spring operates is increased as the spring reacts.

12. In a counter provided with revolvable means movable away from zero position to perform a counting operation, said revolvable means including a member movable in an orbit during 40 counting and resetting operations, the combination of resetting mechanism comprising a pick-up element biased for movement into said orbit to engage said member and return said revolvable 45 means toward zero position, retaining means for said element arranged to release said element upon initiation of a resetting operation and to effect the withdrawal of said element from said orbit during a pull-back movement, stop means 50 biased for movement into a position to stop said revolvable means in zero position, retaining means for said stop means arranged to release said stop means during a resetting operation and to withdraw said stop means near the end of a pull-back 55 movement, and means including a spring and leverage system for effecting said pull-back movement wherein the leverage of said system is increased as the spring reacts.

13. In a counter provided with resetting mechanism adapted to engage the counting mechanism during a resetting movement and to release said counting mechanism during a pull-back movement, said resetting mechanism requiring substantial force near the end of said pull-back 60 movement to effect said release; the combination of a cam mounted for movement with said resetting mechanism, a spring, and a follower biased by said spring against said cam, a portion of said 65 cam being shaped to provide a surface extending outwardly from the axis of said cam over which the follower is adapted to move so that the leverage at which the force of the spring is applied to said resetting mechanism is increased as the 70 spring reacts.

14. In a device of the character described wherein a pull-back movement is required with application of substantially constant torque, the combination of a shaft, a cam mounted on said shaft, an arm pivoted adjacent said shaft, a roller 5 carried by said arm, and a spring operatively associated with said arm to force said roller against said cam, the pull-back portion of the cam surface being extended outwardly from the axis of said shaft so that the force of the roller is applied to said shaft at increasing leverage as the 10 spring reacts.

15. In a device of the character described wherein a pull-back movement is required with application of substantially constant torque, the 15 combination of a cam having a surface extending outwardly from the axis of rotation, a follower, means providing a variable force for urging said follower against said surface, and said follower being pivotally mounted at a point offset from 20 the axis of said cam so that the leverage at which said force is applied to said cam is adapted to be varied as said force is varied.

16. In a counter of the type having at least a first and a second numeral wheel each rotatably mounted on a supporting shaft and transfer mechanism including a lock disc and a transfer pinion to drive said second wheel a fraction of a rotation for each complete rotation of said first wheel, the transfer pinion being secured to said shaft 25 30 whereby rotation of said shaft is adapted to return said second wheel to zero position; the combination of resetting mechanism adapted to control the movement of said shaft and also return said first wheel to zero position comprising means 35 to move said shaft during a resetting operation, pick-up means movable to a position upon initiation of a resetting operation to return said first wheel to zero position, means movable to a 40 position after initial movement of said pick-up means to stop said first wheel in zero position, and means for moving said pick-up means and said stop means upon completion of said resetting operation to free said first wheel for a new 45 counting operation.

17. In a counter of the type having at least a first and a second numeral wheel each rotatably mounted on a supporting shaft and transfer mechanism including a lock disc and a transfer pinion to drive said second wheel a fraction of a rotation for each complete rotation of said first wheel, the transfer pinion being secured to said shaft 50 whereby rotation of said shaft is adapted to return said second wheel to zero position; the combination of resetting mechanism adapted to control the movement of said shaft and also return said first wheel to zero position comprising a reset shaft, means associated with said reset shaft for releasably locking said supporting shaft during a counting operation and to drive said supporting shaft during a resetting operation, means associated with said reset shaft including an element movable to a position upon initiation of the 55 resetting operation to return said first wheel toward zero position, means movable to a position after initial movement of said element to stop said first wheel in zero position, and means operable after said first wheel has reached zero position to release said first wheel and releasably lock 60 said supporting shaft.

18. In a computer having a counter for indicating the amount and another counter for indicating the cost of units being computed; the combination of resetting mechanism adapted to si- 75

multaneously reset each counter backwards to zero position comprising a reset shaft, pick-up means associated with said reset shaft for movement during a resetting operation to return each counter backwards toward zero position, each of said counters being provided with an engageable lug, means biased to a position to engage and stop said lugs in zero position, means operable when

said counters have reached zero position to effect a pull-back movement on said shaft, and means associated with said shaft for effecting movement of said stop means to lug engaging position during the resetting operation and from lug engaging position during the pull-back movement.

5

CHARLES S. HAZARD.
